UNITED STATES PATENT OFFICE.

LEE M. VANCE, OF DAVIS, CALIFORNIA, ASSIGNOR TO THE VANCE COMPANY
INCORPORATED.

STAPLE-RETAINER.

1,127,117.

Specification of Letters Patent.

Patented Feb. 2, 1915.

Application filed July 28, 1914. Serial No. 853,744.

To all whom it may concern:

Be it known that I, LEE M. VANCE, citizen of the United States, residing at Davis, in the county of Yolo and State of California, have invented certain new and useful Improvements in Staple-Retainers, of which the following is a specification.

This invention relates to new and useful improvements in staple retainers of the type 10 employed in connection with concrete or other plastic posts of a similar nature.

One of the principal objects of the invention is to construct the retainer with such 15 regard to proportion, number and arrangement of parts that it may be cheaply manufactured, will be durable and efficient in service and may be easily and quickly applied to the post with a minimum expenditure of time and labor.

Another and more specific object of the invention is to provide a retainer which is formed from a single sheet of metal of substantially trapezoidal shape and consists essentially of a body portion, a triangular 25 tongue, and a pair of staple receiving channels which converge toward the tongue and are produced by rolling the non-parallel edges of the body portion so as to form tubes.

A further object is to form the tubular members, which receive the shanks of the staple, in such a manner that their most widely separated terminals may be crimped or flattened so as to form a closure, making 35 it impossible for the concrete to enter the tubular members during the molding of the post.

A still further object and one of equal importance with the foregoing is to locate 40 the tongue, referred to above, in such relation to the open terminals of the tubes that these terminals of the tubes will be closed by the mold pallet when the tongue of the retainer is inserted therein during the manufacture of the post.

The above recited and other incidental objects of a similar nature are accomplished by such means as are illustrated in the accompanying drawings, described in the following specification and then more particularly pointed out in the claims which are appended hereto and form a part of this application.

Referring now to the drawings, wherein there has been illustrated the preferred embodiment of this invention as it is reduced to practice, and throughout the several views of which similar reference characters designate corresponding parts, Figure 1 is a perspective view of a concrete post provided 55 with a pair of the staple retainers; Fig. 2 is a section on the line 2—2 of Fig. 4, and disclosing the retainer as embedded in a post; Fig. 3 is a similar view taken on the line 3—3 of Fig. 4; Fig. 4 is a detail perspective view of the staple retainer in disassembled position; Fig. 5 is a view of the blank from which the retainer is formed.

The single sheet metal blank from which my staple retainer is fashioned is illustrated 70 in detail in Fig. 5. By referring to this figure, it will be seen that the blank is substantially trapezoidal in shape and that the edge 10 (which is the shorter of the two parallel edges) is cut away to produce a 75 substantially triangular tongue 11 which is centrally located with respect to the edge 10. This tongue member 11 is adapted to be inserted in the pallet of the mold for properly 80 positioning the retainer during the manufacture of the post, in a manner which will be hereinafter further described.

It will be seen that the cutting away of the edge 10 of the blank to form the tongue 11 results in the formation of the terminal 85 lobes A and B. These members A and B are rounded so that, when the staple receiving tubes are formed (in a manner which will be hereinafter described), their forward terminals will be provided with a circular 90 edge which lies flush with the straight edges C and D. The corners of the blank are cut-away, as at E and F, so that the rear terminals of the staple receiving tubes will lie flush with the longer of the parallel edges 95 of the blank.

As shown particularly in Fig. 4, the non-parallel edges 12 and 13 of the blank are rolled over a former to produce the tubes 14 and 15. These tubes converge in the direction of the shorter edge 10 of the body of the retainer. Those terminals of the tubes 14 and 15, which are adjacent the longer edge 16, are flattened or crimped, as indicated at 19 and 20, so that a closure is provided for one terminal of each tube. The

other terminals of the tubes are open, being thus formed with the obvious purpose of admitting the shanks of a staple.

From the foregoing description, it will be plainly seen that, when the tongue is inserted in a metal pallet, the normally open terminals of the tubes will be closed by the pallet so that, when the concrete or plastic material of which the post is to be made is tamped in the mold and about the retainer, none of the material may enter the tube.

In concluding the description of my invention, I desire to particularly emphasize the fact that my chief aim has been to produce a staple retainer which may be manufactured at the lowest possible cost, but which will, at the same time, be possessed of all the necessary attributes of an efficient retainer. Apparently, I have accomplished this end by forming a retainer from a single sheet of metal which is shaped to provide not only tubular members for receiving staple shanks, but also a tongue which may be inserted in the mold pallet for positioning the retainer and for closing the open terminals of the tubes.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desired to emphasize the fact that various minor changes in details of construction, proportion and arrangement of parts may be resorted to, when required, without sacrificing any of the advantages of this invention, as defined in the appended claims.

Having thus described the invention, what is claimed as new is:

1. A staple retainer including a substantially trapezoidal body portion, staple receiving tubes formed by rolling the non-parallel edges thereof, and a tongue extending from the shorter of the parallel edges of

the body portion, the body upon opposite sides of the tongue being cut-away to provide rounded edges.

2. A staple retainer formed from a single blank of metal and including a trapezoidal body portion, a pointed tongue extending from the shorter of the parallel edges thereof, non-parallel staple receiving members formed by bending inwardly the non-parallel edges of the body portion, the most widely spaced terminals of the staple receiving members being flattened to form closures.

3. A staple retainer formed from a single blank of metal of substantially trapezoidal form and including a body portion, a substantially triangular tongue extending from the shorter edge thereof, and integrally formed staple receiving tubes located at the non-parallel edges of the body portion, the closely spaced terminals of the tubes being open and the widely spaced terminals of the tubes being closed by flattening the metal thereof.

4. A blank for a staple retainer of the character described formed from a substantially trapezoidal sheet metal blank, having the shorter of its two parallel edges cut away to produce a centrally located triangular tongue, and a pair of terminal lobes, and having the terminals of the longer of the two parallel edges cut away, producing rounded corners.

5. A sheet metal blank for staple retainers, said blank being substantially trapezoidal in shape and having the intermediate portion of the shorter of its two parallel edges cut away to produce a centrally located tongue and terminally disposed lobes which are spaced from the tongue.

In testimony whereof I affix my signature in presence of two witnesses.

LEE M. VANCE. [L.S.]
